2,535,193

PROCESS FOR MAKING HYDROCARBON-LEAD COMPOUNDS

George Calingaert and Hymin Shapiro, Detroit,
Mich., assignors to Ethyl Corporation, New
York, N. Y., a corporation of Delaware

No Drawing. Application December 24, 1949,
Serial No. 135,021

7 Claims. (Cl. 260—437)

1

This invention relates to a process for the manufacture of hydrocarbon-lead compounds, particularly alkyllead compounds. More specifically our invention is directed to an improved process for the manufacture of tetraethyllead.

The process employed in present commercial practice for the manufacture of tetraethyllead has been in use for a number of years and, in general, is satisfactory. However, it has certain disadvantages which are overcome by practicing our invention. The present commercial process proceeds by reacting a sodium-lead alloy of composition controlled to correspond substantially to NaPb with ethyl chloride according to the equation:

With the highest yields obtained thereby, only about 22 per cent of the lead present in the NaPb alloy is converted to tetraethyllead. Under conditions of best operation no one heretofore, as far as we are aware, has been able to increase this yield of tetraethyllead by even a few per cent, due to the inherent limitation in yield as is apparent from consideration of the above equation. It should be noted that in this reaction at least 75% of the lead originally employed is not alkylated. Thus in this reaction, large quantities of lead must be recovered and reprocessed to NaPb alloy in order to make it economical. A further disadvantage of such a large quantity of unreacted lead is that valuable reaction space in the reaction vessel is occupied by materials which are essentially inert for the manufacture of tetraethyllead under present conditions and mode of operation.

Various other processes for the production of alkyllead compounds have been described in the literature. For the most part, however, these prior art methods are subject to the same disadvantage that very large amounts of the lead alloy or lead salt entering into the reaction are converted to free lead instead of the desired alkyllead compound. For example, the well-known Grignard reaction has been suggested frequently for the manufacture of these compounds, as exemplified by U. S. Patents Nos. 1,689,075; 1,705,723; 1,798,593; 1,805,756; 1,863,451; 1,949-948, and other United States or foreign patents of a similar nature. It is evident from a consideration of the equation for the Grignard reaction that a maximum of 50% of the lead in the lead chloride can be converted to tetraethyllead;

2

While the above patents attempt to improve the efficiency of the Grignard reaction upon which they are dependent, they are all subject to the disadvantage that even though the yield approaches the theoretical, 50% or more of the lead which enters into the reaction is not converted to alkyllead but is left as free lead.

Further, the free lead produced in the Grignard reaction will not react with additional quantities of $\text{C}_2\text{H}_5\text{MgCl}$ and thus it must be recovered, purified, and if reused, converted to lead chloride. This is tedious, expensive and inefficient. In part, it accounts for the fact that, so far as we are aware, the Grignard reaction has never been applied to any extent commercially to the production of tetraethyllead or any other organic lead compounds. Despite its drawbacks, therefore, the present commercial operation is a more efficient and desirable process than any based upon the Grignard reaction, due in part to the high cost of lead chloride and the expense involved in reconverting the free lead to lead chloride.

It is therefore an object of our invention to provide a process for the manufacture of alkyllead or aryllead compounds which overcomes the above objections to the present commercial process and which is far superior to the Grignard process. Particularly it is an object of our invention to increase the conversion of lead to tetraethyllead above that obtained in the present commercial practice. Another object of our invention is to increase the product output of tetraethyllead using the existing equipment of the present commercial process. It is a further object to produce tetraethyllead and related compounds by a process which can convert more of the lead charged to the reaction into the desired end product, thereby avoiding the expensive reprocessing of large quantities of lead.

We accomplish these objects by reacting lead such as the lead produced in the present commercial process with an alkylating or arylating agent such as an alkyl chloride and an alkyl- or aryl-magnesium halide corresponding to the general formula RMgX .

In accordance with our invention, we have found that to produce alkyl- or aryllead compounds it is unnecessary to start with either a lead alloy, such as the sodium-lead alloy used in the present commercial process, or with a lead salt such as lead chloride, as in the Grignard process. On the contrary, our invention is in the surprising discovery that hydrocarbon-lead compounds can be made by reacting free lead with an

alkylating or arylating agent and a compound corresponding to the general formula $RMgX$, in which R is a hydrocarbon radical and X is a halide. A typical reaction of our process may be expressed by the following equation:

in which, for example, R may be ethyl and X may be chlorine.

It should be pointed out that free lead will not react with $RMgX$ alone. Both the $RMgX$ and RX type of reagent are needed in our process as contrasted with the Grignard reaction in which lead chloride will react with an ether solution of $RMgX$ with no RX present.

By practicing our invention, yields of over 90 per cent based on the lead charged to the reaction zone have been obtained. Thus, more than a fourfold increase in yield of alkylleads over the present commercial process and almost a two-fold increase over the Grignard process are obtainable by practicing our invention. Such a yield improvement is remarkable and as far as we are aware such high efficiencies in the use of the lead charged are not shown in any of the processes described in the literature, and have not been obtained by the present commercial process.

The lead used in the process of our invention is any form of metallic lead, which from its physical state, degree of comminution, and conditions of surface is reactive with an alkylating or arylating agent and an alkyl- or arylmagnesium halide to produce an alkyl- or aryllead. In general the lead should be finely divided and its surface should be free from oxidation, which would decrease its activity. It is to be noted that substantial yields of tetraethyllead have been obtained in our process from an oxidized form of lead. However, the removal of, or the prevention of the formation of oxidized material on the lead surface materially increases the yield obtainable. The unreacted lead remaining from known processes in which some alkyllead is formed is an especially excellent form of lead for use in our invention. For example, the unreacted lead remaining from the present commercial process, when treated according to our invention with ethyl chloride, and ethylmagnesium chloride, results in a yield of about 70 per cent of alkyllead based on the unreacted lead charged. Thus based on the above actual yield, the lead efficiency, i. e. utilization of the lead in converting it to an alkyllead, is almost 50% greater than that theoretically possible for the Grignard reaction. Based on actual yields obtainable by the most careful control of the Grignard reaction, the lead efficiency in our process is almost 100% greater.

Further examples of lead which can be successfully employed in our process include lead powders resulting from the decomposition of organo-lead compounds by heat, such as for instance, the lead deposited during the thermal decomposition of organo-lead compounds. Certain other forms of lead powders which are sufficiently active for use in making tetraethyllead by our process can be prepared by grinding or otherwise comminuting lead metal or massive lead, especially when this is done in an atmosphere of nitrogen or under an appropriate liquid, which prevents the oxidation of the lead surface. A further example of a method of preparing a finely divided lead suitable for practicing our invention is the reductive precipitation

of lead from its compounds. Other methods such as electrolytic deposition will occur to those skilled in the art.

Lead alloys, particularly those containing alkaline earth and alkali metals, are also a good source of lead and have been successfully employed. Sodium-lead alloy is an especially good alloy for such use. Other examples of metals alloyed with the lead which can be successfully used in practicing our invention are calcium, potassium, and magnesium. In general any alloy which will react in the following equation can be employed as a source of lead for our process:

Our invention is adaptable to the production of alkyllead, aryllead or mixed alkylaryllead compounds generally, such as tetraethyllead, tetramethyllead, dimethyldiethyllead, triethyl-phenyllead, tetrapropyllead, and tetraphenyl-lead. Nevertheless, for convenience in describing our invention hereafter, specific reference will be made to tetraethyllead, the most widely known because of its use as an antiknock. Whenever in the following description this material is referred to it is to be understood that other alkyl or aryllead compounds or mixtures can be made by our process.

Generally the process of our invention is conducted as follows: lead, for example in the form of sodium-lead alloy, $NaPb$, is first placed in a reaction vessel such as the autoclave of the present commercial process. The alkylmagnesium halide may also be added at this time although it is preferable to add it after the reaction vessel is closed. The vessel is then closed except for the liquid feed line through which the fluid reactants are passed and a line to a reflux condenser. The necessary quantity of alkylating agent such as ethyl chloride is then introduced into the autoclave followed by delivery of the alkylmagnesium halide such as ethylmagnesium chloride, or the latter can be added along with the ethyl chloride. In the former method, if the lead is introduced in the form of sodium-lead alloy, the ethylmagnesium chloride is added after the customary reaction between the alloy and the alkylating agent is initiated. In one preferred modification of our invention the alkylmagnesium chloride is not added until most of the customary reaction between the alloy and the alkylating agent has occurred. In both methods of operation a dual process is occurring, namely the customary reaction between the sodium-lead alloy and the ethyl chloride, and the reaction of the free lead formed in such reaction with additional ethyl chloride and the ethylmagnesium chloride.

Thus, the preferred methods of operating our process using a lead alloy such as sodium-lead alloy, are the method of reaction wherein the alkylmagnesium halide is added prior to or concurrently with the alkylating agent, hereinafter referred to as the one-stage process, and the method wherein most of the alkylmagnesium halide along with additional quantities of alkylating agent is added after the customary reaction is substantially completed, hereinafter referred to as the two-stage process. Of course, variations in the above modifications can be made such as introducing part of the alkylmagnesium halide along with the initial feed of the alkylating agent followed by additional alkylmagnesium halide

5

after most of the customary reaction has occurred. Also while it is preferable in our two-stage embodiment to add only the amount of alkylating agent usually employed for the first stage and then add the amount required for the second stage, it is within the scope of our invention to add most of the alkylating agent in the first stage and primarily only the alkylmagnesium halide in the second stage. Further, while the above general description of our process as well as the detailed examples which follow are descriptive of a batch-type operation, it is to be understood that the process of our invention may also be conducted in a continuous manner wherein the lead and the alkylation or arylation agent and the hydrocarbonmagnesium halide are brought together continuously in any suitable reaction zone.

Unless otherwise stated all parts and percentages herein are by weight. Further in the following examples, ether refers to diethyl ether unless otherwise specified.

Our invention can be further understood by referring to the following illustrations of detailed working examples:

EXAMPLE I

(Two-stage reaction using sodium-lead alloy and ethyl chloride)

A charge of 100 parts of NaPb alloy was added to a reaction vessel equipped with an agitator, a jacket for circulation of heating or cooling liquids, a reflux condenser, charging and discharging ports, liquid feed lines, and means for releasing the pressure. Liquid ethyl chloride in the amount of 167 parts was added under pressure to the stirred solids in the vessel over a period of one-half hour. By controlling the flow of liquid in the autoclave jacket and in the reflux condenser the temperature of the reaction mass was permitted to rise from an initial temperature of 50° C. to a temperature of 70° C. during this feed period. The pressure in the autoclave during this feed rose to 75 pounds per square inch gauge where it was maintained. The temperature of the stirred reaction mixture was maintained at 70° C. for an additional 15 minutes maintaining the 75-pound pressure. While the above operation was carried out, 15.7 parts of magnesium chips were placed in a separate reaction vessel equipped with an agitator, a jacket for circulating heating or cooling liquids, reflux condenser, liquid feed lines, solid feed means and lines for providing an inert atmosphere and controlling the pressure. A mixture of 4 parts of ethyl chloride and 2 parts of diethyl ether was added all at once to the magnesium at a temperature of 25° C. in the closed reaction vessel. After five minutes of agitation, 93.8 parts of ether was added at a temperature of 25° C. over a period of 10 minutes, followed by 37.7 parts of ethyl chloride added over a period of one hour, during which time the temperature varied between 30 and 55° C. and the pressure was maintained between a pressure of 30 to 40 pounds per square inch gauge. After the addition was complete, agitation was maintained for an additional 90 minutes. At the end of this period the thus formed solution of ethylmagnesium chloride in ether was transferred by nitrogen pressure to the autoclave of the alkyllead reaction through a line connecting the two vessels. The ethyl chloride added at the beginning of the first stage, which was in excess over that required to alkylate the sodium-lead alloy in the first

6

stage, remained for further reaction in the second stage. The autoclave was maintained at a temperature of 70° C. and a pressure of approximately 130 pounds per square inch gauge for an additional 80 minutes. At the end of this period the pressure in the autoclave was reduced to atmospheric by venting for 15 minutes while the temperature was maintained at 70° C. For an additional period of 15 minutes at 70° C. nitrogen was passed over the reaction mass with the autoclave open to the atmosphere. The mass was then cooled to 45° C. over an additional 30 minute period while flushing with a stream of nitrogen. The reaction mass was then discharged to a steam-still containing 250 parts of water. With 100° C. steam fed to the jacket of the steam-still, a forecut of ethyl chloride and ether was taken, up to a vapor temperature of 70° C. At this point the steam jets were turned on, and with the jacket steam off, the tetraethyllead was distilled for one and one-half hours after the first drop of tetraethyllead appeared in the distillation receiver. The yield of product was 117 parts, or a yield of 83.5 per cent based on the lead present in the sodium-lead alloy.

EXAMPLE II

(One-stage reaction using sodium-lead alloy and ethyl chloride)

Using substantially the same operating procedure as described in the above detailed example, a one-stage modification was carried out with the variation that the ether solution of ethylmagnesium chloride was added simultaneously with the charge of ethyl chloride to the alkyllead autoclave containing the sodium-lead alloy over a period of 45 minutes. In this process 100 parts of sodium-lead alloy, 167 parts of ethyl chloride, 57.4 parts of ethylmagnesium chloride and 95.9 parts of ether were employed. The operations of cooking, venting, cooling, discharging and recovery of the product were conducted substantially as above. The yield of product was 66.7 parts, or 47.5 per cent based on the lead present in the sodium-lead alloy.

EXAMPLE III

The process of Example I was carried out until the reaction between the ethyl chloride and the sodium-lead alloy was substantially complete, that is after the cooking period of 15 minutes at a temperature of 70° C. was completed. The autoclave was then vented to atmospheric pressure over a period of 15 minutes with the agitator in motion and the temperature maintained at 70° C., thereby removing substantially all the unreacted ethyl chloride. A solution of 57.4 parts of ethylmagnesium chloride in 95.8 parts of ether and containing an additional 167 parts of ethyl chloride was then added to the autoclave during a period of 45 minutes. The operations of cooking, venting, cooling, discharging and recovery of the product were conducted substantially as in Example I above. The yield of product was 117 parts, or 83.5 per cent based on the lead present in the sodium-lead alloy.

EXAMPLE IV

In place of the sodium-lead alloy of the foregoing examples 100 parts of a lead powder were added to the autoclave and 250 parts of ethyl chloride, and 85.7 parts of ethyl magnesium chloride in 143 parts of ether were added in the sequence and under the conditions of Example II. The additional operations of cooking, venting,

cooling, discharging and recovery of the product were conducted substantially as in Example I above. The yield of product was 109 parts, or 77.8 per cent based on the lead metal charged.

Various alkylating and arylating agents can be employed in our invention. In general the alkylating and arylating agents of our process are organic compounds which may be represented by RX, having the desired alkyl or aryl group, R, attached to a negative atom or radical, X, capable of reacting with the magnesium of the hydrocarbon-magnesium halide to form the corresponding magnesium salts, MgX₂, as shown in the above equation for a typical embodiment of the process of our invention. For the most part these alkylating and arylating agents are esters of inorganic acids such as the alkyl and aryl chlorides, bromides, iodides and phosphates. In general the inorganic acid ester alkylating and arylating agents are the monochloro, -bromo and -iodo derivatives of the paraffin and aromatic hydrocarbons such as methane, ethane, propane, butane, pentane, and benzene and the corresponding trialkyl phosphates. For example methyl chloride, methyl iodide, ethyl chloride, ethyl bromide, ethyl iodide, n-propyl chloride, n-butyl chloride, n-butyl bromide, n-amyl chloride, n-amyl iodide, phenyl bromide and triethyl phosphate can be successfully employed. Instead of the normal alkyl halides, other isomers such as the iso compounds can be used. Various combinations of these alkylating agents can also be used. For example two or more alkylating or arylating agents can be used simultaneously in the one- and two-stage process or different alkylating or arylating agents can be used in each stage of the two-stage process.

The different alkylating and arylating agents mentioned above do not all behave in the same manner. The operating conditions can be varied within the scope of our invention in order to obtain the best results with the particular alkylating agent or agents employed. For example, except for methyl chloride, the lower alkyl chlorides, particularly ethyl chloride, give excellent yields of tetraalkyllead in both the one- and two-stage operations with sodium-lead alloy. However, methyl chloride and the alkyl bromides and iodides are preferably employed in the second step of the two-stage operation since better yields are thereby obtained.

In general, the alkylating agents which are well known for use in the present commercial process, or which can be used in our process with a lead alloy, give excellent results when employed in all embodiments of our invention. Those alkylating or arylating agents which give relatively low yields in the present commercial process, or in our process in which a lead alloy is employed, do, however, give excellent results when free lead or the lead resulting from the processes of the prior art are employed, or are employed in the second stage of the two-stage embodiment of our invention, regardless of the form in which the lead is employed in the first stage.

For best results, the alkylating and arylating agents of our process should be employed in excess over the amount required according to the equation for our reaction as given previously herein. If less than the amount of alkylating agent required to completely alkylate the lead according to the above equation of a typical example of our process is used, the yields will be lower, but will still be good when determined on the basis of the amount of alkylating agent. This is es-

pecially true when the two-stage operation is employed and in an operation wherein the alkylating agent is fed to the system gradually in a batch or continuous operation.

The hydrocarbon-magnesium halide of our process, illustrated by the RMgX in the above typical equation of our process, consists of the desired alkyl or aryl radical, R, and a halide, X, selected from chlorine, bromine or iodine. Thus, for example, we can employ in the process of our invention ethylmagnesium chloride, ethylmagnesium bromide, ethylmagnesium iodide, methylmagnesium chloride, methylmagnesium bromide, methylmagnesium iodide, n-propylmagnesium chloride, n-propylmagnesium bromide, n-butylmagnesium chloride, n-butylmagnesium bromide, n-butylmagnesium iodide, phenylmagnesium chloride, phenylmagnesium bromide and phenylmagnesium iodide, prepared by reacting ethyl chloride, ethyl bromide, ethyl iodide, methyl chloride, methyl bromide, methyl iodide, n-propyl chloride, n-propyl bromide, n-butyl bromide, n-butyl iodide, phenyl chloride, phenyl bromide and phenyl iodide respectively with metallic magnesium. Instead of the hydrocarbon-magnesium halides prepared by reacting normal alkyl halides with metallic magnesium, other isomers can be employed such as those derived from the iso and secondary alkyl halides. Various combinations of hydrocarbon-magnesium halides can also be used.

Any of the usual solvents or catalysts normally employed in the preparation of hydrocarbon-magnesium halides can be successfully employed in preparing hydrocarbon-magnesium halides for use in the process of our invention. Examples of such solvents which can be employed include the aliphatic ethers such as diethyl ether, methyl-ethyl ether, diisopropyl ether and dibutyl ether, the aliphatic ethers of the polyhydroxy alcohol's, such as the dimethyl ether of ethylene glycol, and various amines such as triethylamine, aniline, dimethylaniline and diphenylamine. We have also found that various catalysts or reaction starters, such as iodine or mercury, often employed to initiate the reaction between the organic halide and the magnesium, do not interfere with the subsequent use of the hydrocarbon-magnesium halide in the process of our invention.

The hydrocarbon-magnesium halide employed in our invention can be prepared by any one of the well-known methods. For example, in one embodiment of our invention the hydrocarbon-magnesium halide can be prepared by the addition to magnesium metal of a solution of an organic halide in diethyl ether, and allowing reaction to take place until all the magnesium is reacted and dissolved therein, and then adding this solution of hydrocarbon-magnesium halide in ether to the other reactants of our invention in the manner described heretofore. In a further embodiment of our invention, the ether or other solvent or catalyst employed in the preparation of the hydrocarbon-magnesium halide may be removed by evaporation and the resulting solid reaction product employed in the process of our invention. Thus, we have found that the amount of ether or solvent commonly employed in the manufacture of the hydrocarbon-magnesium halide is not critical and we have obtained excellent results with hydrocarbon-magnesium halides either dissolved in appropriate solvents or as a dry solid. Furthermore, it is sometimes convenient to introduce the hydrocarbon-magnesium halide to the reaction zone as a slurry, and for

this purpose the solvent and excess organic halide is only partially evaporated until the hydrocarbon-magnesium halide begins to separate from solution. Thus, depending on the type of operation, that is batch, semi-continuous, or continuous the amount of solvent or carrier liquid can be varied so as to produce the most efficient operation. Thus in the two-stage embodiment of our invention described in Example I we have employed, along with the 100 parts of sodium-lead alloy and 167 parts of ethyl chloride of the first stage, 57.4 parts of ethylmagnesium chloride with 22.4, 95.8, 192 and 287 parts of ether and obtained yields of alkyllead product of 56.6, 112, 92.1 and 66.6 parts respectively or 49.3, 83.5, 65.6 and 47.4 per cent based on the lead in the sodium-lead alloy.

We have, however, found that for the successful operation of the process of our invention the hydrocarbon-magnesium halide can be prepared in the complete absence of the ether or other activating solvent usually associated with the preparation of these compounds. Further, the addition of such solvent to the hydrocarbon-magnesium halide prepared in its absence is likewise not necessary for the successful operation of our process. For example, we prepared ethylmagnesium iodide by treating powdered magnesium with ethyl iodide dissolved in benzene containing a trace of iodine. After reaction, the benzene and excess ethyl iodide were removed, leaving a dry, free-flowing gray powder, which was successfully employed in the process of our invention as follows: To the residue remaining in the autoclave after the reaction of 100 parts of sodium-lead alloy with 167 parts of ethyl chloride according to the procedure of Example III, was added 140.4 parts of the above-described dry ethylmagnesium iodide and 252 parts of ethyl chloride. After the operation of cooking, venting, cooling and discharging, the yield of product was 65.8 parts or 46.9 per cent based on the lead in the sodium-lead alloy.

The process of our invention is not limited to the preparation of tetraalkyllead or tetraaryllead compounds in which each of the four alkyl or aryl groups attached to the lead atom is the same, as in tetraethyllead or tetraphenyllead, but also includes the preparation of mixed alkyllead compounds, mixed aryllead compounds and mixed arylalkyllead compounds. Thus we may illustrate a typical generalization of the process of our invention by the following equation:

wherein each of a , b , c , d , and e is a number between 0 and 1 inclusive and the sum

$$(1-a) + (1-b) + (1-c) + (1-d) + (1-e)$$

equals 1.

In this presentation of the process of our invention R and R' may be the same or different and X and Y may be the same or different. Thus R and R' include alkyl and aryl radicals, X represents a halogen chosen from the class of chlorine, bromine and iodine, and Y includes in addition to these halogens such negative atoms or radicals as are capable of forming magnesium salts with the magnesium of the hydrocarbon-magnesium halide, as for example the phosphate radical.

It should be pointed out that in the above typical general equation for our process the use of a catalyst is not mentioned. The hydro-

carbon-magnesium halide is prepared in the usual way, involving use of an activating solvent and catalyst. No further quantities of catalyst or activating solvents are required for the successful operation of our process, although the use of such additional quantities is, in some cases, beneficial.

To illustrate an embodiment of our process wherein the alkyl group of the alkylating agent and the alkyl group of the hydrocarbon-magnesium halide are different we conducted a series of operations employing the procedure of Example III, wherein the lead remaining from the reaction of 100 parts of sodium-lead alloy with 167 parts of ethyl chloride was subsequently reacted with 203 parts of *n*-propyl chloride, 167 parts of ethyl chloride or 131 parts of methyl chloride paired with 57.4 parts of ethylmagnesium chloride, 66.5 parts of *n*-propylmagnesium chloride or 57.4 parts of ethylmagnesium chloride, respectively, each in 95.9 parts of ether. Thus, in this example, wherein R and R' were different, but were both alkyl groups, yields of 91.8, 86.9 and 78.2 per cent of alkyllead product based on the lead in the sodium-lead alloy were obtained, respectively. Similarly, as examples of the process of our invention wherein the R and R' of the above typical generalized equation were the same or different, and one or both were aryl, we carried out operations similar to Example III, wherein the organic halide of the second stage was 409 parts of phenyl bromide employed with either 118 parts of ethylmagnesium bromide or 57.4 parts of ethylmagnesium chloride each in 95.8 parts of ether, the yield of product was 44.7 and 53.6 per cent respectively based on the lead in the sodium-lead alloy. The arylating agent and arylmagnesium halide likewise can be employed in the one-stage process of Example I but the yield, although much higher than that obtained in the present commercial process is somewhat lower than in our preferred two-stage embodiment.

As shown heretofore it is not essential for the process of our invention that chloro alkylating and arylating agents or hydrocarbon-magnesium chlorides be employed. As further illustration we reacted 406 parts of ethyl iodide and 117 parts of ethylmagnesium iodide in 95.8 parts of ether with the lead remaining from an operation similar to Example III and according to the further procedure of that example. There was obtained 119 parts of product or a yield of 84.5 per cent based on the lead charged as sodium lead alloy. Similarly using 284 parts of ethyl bromide and 86.2 parts of ethylmagnesium bromide in 95.8 parts of ether in the second stage, there was obtained 119 parts of product or a yield of 84.5 per cent based on the lead in the sodium-lead alloy.

To illustrate that for the successful operation of the process of our invention the negative, or Y , group of the alkylating agent, $\text{R}'\text{Y}$, and the X group of the hydrocarbon-magnesium halide RMgX need not be the same, we conducted a series of two-stage operations similar to that of Example III wherein the lead from 100 parts of the sodium-lead alloy of the first stage was reacted with the following reagent pairs: 406 parts of ethyl iodide plus 57.4 parts of ethylmagnesium chloride; 167 parts of ethyl chloride plus 117 parts of ethylmagnesium iodide; 284 parts of ethyl bromide plus 57.4 parts of ethylmagnesium chloride and 317 parts of triethyl phosphate plus 57.4 parts of ethylmagnesium chloride, in each instance in the presence of 95.8 parts of ether. The yield of product in the four

11

operations was 125, 89.7, 129 and 59.7 parts or 89.1, 63.9, 91.9 and 42.5 percent, respectively, based on the lead introduced in the first stage.

As a further example of an embodiment of our process wherein the R' of the alkylating agent and the R of the hydrocarbon-magnesium halide are different but are both alkyl, and wherein the negative group of the alkylating agent and the halide of the hydrocarbon-magnesium halide are also different, we reacted in the second stage of the two-stage operation of Example III, 57.4 parts of ethylmagnesium chloride, 550 parts of methyl iodide and 95.8 parts of ether. The yield of product was 83.9 per cent based on the lead in the sodium-lead alloy employed in the first stage.

The importance of the alkylating or arylating agent in combination with the hydrocarbon-magnesium halide of our invention is shown in the following series of operations. In one instance the procedure of Example I was followed until the reaction between the ethyl chloride and the sodium-lead alloy was complete, and the product was then discharged from the autoclave and recovered. From 100 parts of sodium-lead alloy was obtained 31.2 parts of product, or a yield of 22.1 per cent based on the lead in the sodium-lead alloy, which is normal for the present commercial process. In a second instance the procedure of Example III was followed with exception that the ethyl chloride was not reintroduced along with the ethylmagnesium chloride and the ether. After the subsequent operations described in Example III the yield of product from 100 parts of sodium lead alloy was 31 parts, or 22 per cent based on the lead in the sodium-lead alloy, a result not substantially different from the yield obtained by the present commercial process. As shown in Example III by reintroducing the ethyl chloride along with the ethylmagnesium chloride and the ether a yield of 117 parts of product or 83.5 per cent was obtained from the 100 parts of sodium-lead alloy.

While the process of our invention is operable over a wide range of temperatures and gives good results at temperatures as low as 20° C., we have found that our preferred temperature is within the range of 45° C. to 85° C. When our two-stage reaction is employed it is sometimes advantageous to operate the second stage at a different temperature than the first stage. However, temperatures preferably in the neighborhood of 70° C. are employed in both the one-stage and two-stage operations.

The amount of hydrocarbon-magnesium halide is not critical in the process of our invention. For example, in the manufacture of tetraethyllead we have obtained high efficiency in the utilization of the ethylmagnesium chloride and good yields of product based on the lead employed when the ethylmagnesium chloride was used in amounts between about 6 and 60 parts per 100 parts of lead. Above this amount the yield based on lead is still high, but the improvement in yield based on the ethylmagnesium chloride diminishes.

In general, the reaction of our process is completed within a few hours, i. e. 1/2 to 8 hours. When it is coupled with the present sodium-lead alloy method, we have found that a total time within the range of approximately 1/2 to 6 hours is sufficient.

It is desirable to introduce the alkylating agent such as ethyl chloride as a liquid. Therefore the autoclave is operated under a pressure suffi-

12

ciently high to maintain the fluid reactants in the liquid phase. Thus the pressure in the reaction vessel when using ethyl chloride preferably is maintained within the range of 70 to 150 pounds per square inch gauge.

For the process of our invention we have employed other alloys than sodium-lead alloy in either a one- or two-stage operation. Thus, employing 100 parts of a calcium-lead alloy, having a composition corresponding to the formula CaPb, with 300 parts of ethyl chloride in the first stage of an operation similar to that of Example I, and in the second stage the solution prepared from 14.7 parts of magnesium, 38.9 parts of ethyl chloride and 89.8 parts of ether, we obtained 107 parts of product or a yield of 76.1 per cent based on the lead in the calcium-lead alloy.

Our process, in common with most of the processes of the prior art, when employed to make tetraethyllead also produced some hexaethyllead. Its presence is readily detected by noting the color in the final alkyllead product. If there is none present the color is water-white while a yellow color indicates its presence. In view of the widespread commercial use of tetraethyllead, it may be desirable to convert hexaethyllead to a more valuable product. Therefore any of the latter container in the final product can be converted to tetraethyllead and free lead by heating. Actually, by such heating, 82% by weight of tetraethyllead is formed and the free lead so produced can be reprocessed. Further, most of the hexaethyllead can be prevented from forming in our process by employing temperatures near 85° C. or by lengthening the time of the reaction at a lower temperature, say 70° C.

For the reaction of our invention to proceed effectively it is preferred that the reaction zone be free from substantial amounts of certain materials which may be inert and which may act primarily as diluents. However certain materials when used in small concentrations are, in some cases, beneficial even though they do not directly improve the yields. For example, certain thermal stabilizers such as diisobutylene, styrene and naphthalene, when added in quantities of the order of a few per cent based on the lead, may be beneficial in reducing the tendency of the alkyllead compounds in the reaction mass to undergo thermal decomposition. Further, certain known "accelerators" such as acetone, dipropyl ketone, ethyl acetate, ethyl butyrate and butyl acetate may tend to accelerate the reaction when used in small quantities of the order of .04 part to 1 part of lead. Excessive quantities should be avoided.

Hydrocarbons, such as commercial gasoline are additional examples of materials which may be beneficial in small quantities, but harmful when used in excess. The presence of such hydrocarbons in substantial amounts tends to interfere with the progress of the alkylation reaction, particularly in the one-stage embodiment of our invention, although relatively small amounts may be of some help. In general, as the amount of such hydrocarbons is increased, the yield of tetraalkyllead is reduced until finally little, if any, is produced.

Other embodiments of this invention can be made without departing from the spirit and scope of our invention which is not limited to the specific embodiments given herein.

We claim:

1. A process for making tetrahydrocarbon,

lead compounds comprising reacting lead with a reagent selected from the class consisting of arylating and alkylating agents which include the hydrocarbon radical in question and have a negative radical which reacts with magnesium, and with a hydrocarbonmagnesium halide in which the hydrocarbon radical is selected from the group consisting of alkyl and aryl and the halide is selected from the group consisting of chlorine, bromine and iodine.

2. A process for making tetrahydrocarbon-lead compounds comprising reacting lead with an alkylating agent having the hydrocarbon radical in question and having a negative radical which reacts with magnesium and with an alkylmagnesium halide.

3. A process for making tetrahydrocarbon-lead compounds comprising reacting a lead alloy with an alkylating agent having the hydrocarbon radical in question and having a negative radical which reacts with magnesium and with an alkylmagnesium halide.

4. A process for making a tetrahydrocarbon-lead compound comprising reacting lead with an inorganic acid ester alkylating agent having the hydrocarbon radical in question and having a negative radical which reacts with magnesium and with an alkylmagnesium halide in which the halide is selected from the group consisting of chlorine, bromine and iodine.

5. A process for making tetraethyllead comprising reacting lead with ethyl chloride and ethylmagnesium chloride.

6. In a process for making a tetrahydrocarbon-lead compound in which both alkyllead and free lead is formed, the improvement comprising reacting said free lead with an inorganic acid ester alkylating agent and an alkylmagnesium halide in which the halide is selected from the group consisting of chlorine, bromine and iodine.

10 7. A dual process for making tetraethyllead comprising treating a sodium-lead alloy with ethyl chloride, and reacting ethyl chloride and ethylmagnesium chloride with the free lead so formed.
